G. H. HAYES.
SPRING SHACKLE.
APPLICATION FILED NOV. 6, 1920.

1,426,064.

Patented Aug. 15, 1922.

Inventor:
GEORGE H. HAYES

UNITED STATES PATENT OFFICE.

GEORGE H. HAYES, OF ST. PAUL, MINNESOTA.

SPRING SHACKLE.

1,426,064.

Specification of Letters Patent. Patented Aug. 15, 1922.

Application filed November 6, 1920. Serial No. 422,313.

To all whom it may concern:

Be it known that I, GEORGE H. HAYES, a citizen of the United States, resident of St. Paul, county of Ramsey, State of Minnesota, have invented certain new and useful Improvements in Spring Shackles, of which the following is a specification.

The object of my invention is to provide a yielding connection between the frame of 10 the vehicle and the forward springs which will take up the jar or forward lurch of the frame when the wheels strike an obstruction or drop into a depression and is designed as a modification or improvement 15 of the device shown in United States Letters Patent No. 1,180,036, issued to me April 18, 1916.

In this patent a compression spring is shown interposed between the members of 20 the shackle. This spring is located at a point where it is intersected by the longitudinal axis of the shackle members. My present invention contemplates the use of two springs, one upon each side of the longitudinal axis of the shackle members for 25 the purpose of eliminating any tendency to lateral lurch or sway of the members and provide for a more even compression of the springs.

30 The invention consists generally in various constructions and combinations, all as hereinafter described and particularly pointed out in the claims.

In the accompanying drawings forming 35 part of this specification,

Figure 1 is a side elevation of the forward portion of a vehicle chassis with my invention applied thereto,

Figure 2 is a detail view, showing the 40 manner of mounting the springs in the shackle,

Figure 3 is a plan view of the shackle,

Figure 4 is a sectional view on the line 4-4 of Figure 3,

45 In the drawing, 2 represents one of the side bars of the chassis and 3 the forward wheel mounted on the axle of the car in the usual way. 4 is a spring of the half elliptic type, pivotally connected at 5 to the forward end of the bar 2. At the rear end of the spring I provide a shackle consisting of a link 6 having its forward end pivoted at 7 to the rear end of the spring, the rear end of the link being pivoted at 8 to a carrier 9 which has a pivotal connection at 10 with a lug 10^a on the side bars of the chassis.

The spring and shackle thus have freedom of movement for the rise and fall of the car frame.

The link and carrier are provided with laterally projecting lugs 11 and 11^a formed integrally therewith, though they may be secured thereto by suitable means, if preferred. A pair of compression springs 12 are arranged between the opposite lugs upon 65 opposite sides of the longitudinal axis of the shackle. The ends of the springs are secured to the lugs by suitable means, such as bolts 13, having washers 14, though any other fastening means suitable for the purpose may be used. The springs will be put under tension upon the initial forward movement or lurch of the vehicle frame. When the forward wheels strike an obstruction or drop into a depression, the vehicle 75 body will be thrown forward and the shock or jar resulting from the sudden checking of such forward movement will be taken up or absorbed by the compression springs and thereby the vehicle will be much easier 80 riding through the presence of the shackle between the springs of the vehicle and the body.

In this form of shackle I provide a comparatively long pivotal bearing between the 85 ends of the shackle members 6 and 9 and the compression springs are widely separated and there is less tendency for the shackle members to lurch or rock one upon the other than where a short bearing is provided and a single compression spring.

The form of the shackle members may, of course, be modified in various ways and still embody the advantageous features herein specified.

I claim as my invention:

1. The combination, with a vehicle frame, of a spring having one end attached to said frame and a shackle pivotally connecting the other end of said spring with said frame, said shackle comprising a link and carrier having a comparatively long pivotal bearing upon one another at one end, the other end of said link and carrier being pivotally connected respectively to said 100 spring and frame, and compression springs interposed between said link and carrier, and separated a considerable distance for 105 yieldingly resisting relative movement of said link and carrier toward one another. 110

2. The combination, with a vehicle frame, of a spring having its forward end at-

tached to said frame and a shackle pivotally connecting the rear end of said spring with said frame, said shackle comprising a link and carrier having a comparatively long pivotal bearing upon one another at their rear ends, the forward ends of said link and carrier being pivotally connected respectively to said spring and frame, and widely separated compression springs interposed between said link and carrier for yieldingly resisting relative movement of said link and carrier toward one another.

3. The combination, with a vehicle frame, of a spring having one end attached to said frame and a shackle pivotally connecting the other end of said spring with said frame, said shackle comprising a link and carrier pivotally connected to one another at one end, the other end of said link and carrier being pivotally connected respectively to said spring and frame, said link and carrier having laterally projecting lugs and compression springs arranged between said lugs and secured thereto and separated a considerable distance thereby for yieldingly resisting relative movement of said link and carrier toward one another.

4. The combination, with a vehicle frame, of a spring having one end attached to said frame and a shackle connecting the other end of said spring with said frame, said shackle comprising a link and carrier having a comparatively long pivotal bearing upon one another at one end, the other end of said link and carrier being connected respectively to said spring and frame, and compression springs interposed between said link and carrier for yieldingly resisting relative movement of said link and carrier toward one another.

5. A spring shackle comprising a link and carrier having a comparatively long pivotal bearing upon one another at one end, and compression springs interposed between said link and carrier for yieldingly resisting their relative movement toward one another, said springs being arranged upon opposite sides of the longitudinal axis of said shackle, said long bearing preventing relative lateral rocking of said link and carrier.

In witness whereof, I have hereunto set my hand this 3d day of November, 1920.

GEORGE H. HAYES.
